[57] CLAIM

The ornamental design for a magnetic disk case, as
shown and described.

DESCRIPTION

FIG. 1 is a perspective view of a magnetic disk case
showing my new design in its opened condition;
FIG. 2 is a left side elevational view thereof;
FIG. 3 is a rear elevational view thereof; and
FIG. 4 is a bottom plan view thereof in the closed position.

FIG. 1

FIG. 2

Fig. 3
